UNITED STATES PATENT OFFICE

150,093

DESIGN FOR A CHASSIS SEAT FOR GLIDER

Harry S. Nagin, Philadelphia, and Ephraim Werner, Pittsburgh, Pa., assignors to Reliance Steel Products Company, McKeesport, Pa., a corporation of Pennsylvania

Application July 20, 1946, Serial No. 131,764

Term of patent 7 years

(Cl. D15—11)

To all whom it may concern:

Be it known that we, Harry S. Nagin and Ephraim Werner, both citizens of the United States, residing respectively in Philadelphia, in the county of Philadelphia and State of Pennsylvania, and Pittsburgh, in the county of Allegheny and State of Pennsylvania, have invented a new, original, and ornamental Design for a Chassis Seat for Glider, of which the following is a specification, reference being had to the accompanying drawing, forming part thereof.

In the drawing,

Figure 1 is a perspective view of the chassis seat for glider; and

Figure 2 is a side elevation of the seat side frames and the glider platform supporting said seat frames.

We claim:

The ornamental design for a chassis seat for glider, substantially as shown.

HARRY S. NAGIN.
EPHRAIM WERNER.
